BUILDING CONSTRUCTION

Charles Suiter and Harold R. Suiter,
Detroit, Mich.

Application September 18, 1937, Serial No. 164,553

8 Claims. (Cl. 72—1)

This invention relates to new and useful improvements in building construction, and the object of the invention is to provide pre-fabricated building elements so related and arranged as to be erected in a minimum of time and at minimum cost.

It is customary generally in constructing various types of buildings, including dwellings, to construct the walls or other portions of brick or block or wood studding, siding etc., that require to be fabricated at the point of erection and thus to a large degree hand made and are not adapted to machine production, and a feature of this invention resides in the provision of pre-formed 15 columns, window frames, door frames, wall panels, ceiling panels etc., of such character as to be readily assembled without necessity of shaping the same at the point of erection.

Pursuant to this general object, we provide 20 pre-fabricated columns, pre-fabricated panels for wall elements with the columns having grooves to receive ends of the panels or tongues provided on frame elements as for windows or doors that may be readily erected to form an enclosure with various wall, floor, ceiling, roofing, and 25 partition elements as hereinafter more specifically described.

A further feature and object of the invention is to provide pre-fabricated elements for the formation of a building which generally consists of 30 a standard size as length of column or width and length of panels and frame elements for doors and windows.

A further feature of the invention is involved 35 in the column construction, the grooving thereof to receive panels or frame elements and the construction of the columns in sections to permit the erection of the building walls in like sections successively one above the other for the height of 40 the building.

A further object of the invention is to provide a new and unique means for supporting a ceiling formed of separate panels in respect to an upper floor or roof structure.

It is further a feature and object of the invention to provide a building of pre-fabricated elements for forming hollow walls with tie members for supporting the pre-fabricated panels in properly spaced relation and providing a chamber that may be filled with insulation such as 50 rock wool or any useable type of insulation material.

A further feature of the invention is involved 55 in the provision of a series of slab-like ceiling elements suspended from above by a new and

unique means permitting the leveling of the various units of the ceiling and the means for uniting the same in edge to edge relationship subsequent to the leveling operation to provide a substantial and rigid ceiling.

The invention further consists in certain structural details that may be required at special points such, for instance, as a window or door frame of pre-fabricated form in the interior of which there is mounted a base frame for the window and 10 which is externally formed to unite the panels or with the columns in a tongue and groove relationship, depending upon its location.

These and other features and objects of the invention are hereinafter more fully described 15 and claimed, and a building structure and parts thereof embodying our invention is shown in the accompanying drawings in which—

Fig. 1 is a side elevation of one form of building which our form and arrangement of pre-fabricated structure is adapted to build.

Fig. 2 is a horizontal section taken substantially on line 2—2 of Fig. 1.

Fig. 3 is a vertical section taken on line 3—3 of Fig. 1 showing a window frame and relationship thereof with the panel walls.

Fig. 4 is a vertical section taken on line 4—4 of Fig. 1.

Fig. 5 is a sectional detail of a corner of the building taken substantially on line 5—5 of Fig. 1.

Fig. 6 is a vertical section taken on line 6—6 of Fig. 5 showing the concrete floor slab and the manner of applying panels to the exterior face thereof and metal beams for supporting the same.

Fig. 7 is an enlarged section through a window and its pre-formed frame taken on line 7—7 of Fig. 1.

Fig. 8 is a horizontal section through a side wall column and the wall and partition panels 40 adjacent thereto.

Fig. 9 is an enlarged vertical cross section of the pre-fabricated wall panels and belt course taken on line 9—9 of Fig. 1.

Fig. 10 is a horizontal section taken on line 45 10—10 of Fig. 9.

Fig. 11 is a fragmentary cross section of the inner wall and support therefor similar to that shown in Fig. 9.

Fig. 12 is a vertical cross section through a 50 floor and ceiling structure therebelow showing the metal framework and manner of supporting the ceiling blocks or panels.

Fig. 13 is a plan view of the group of ceiling panels.

Fig. 14 shows a means of securing the last to be erected ceiling panel in position and manner of adjustment thereof to proper level with the remainder of the ceiling.

5 Fig. 15 is a vertical section of a column formed of pre-fabricated sections.

Fig. 16 is a cross section taken on line 16—16 of Fig. 15.

10 Fig. 17 is a section through a portion of the window frame and belt course taken on line 17—17 of Fig. 1, and showing the tongue and groove relationship thereof.

Fig. 18 is a detail of means for supporting a panel to a floor slab.

15 The system of construction of buildings according to our invention as hereinafter set forth is adapted for the construction of various types of buildings even buildings of several stories in height and as well as dwelling houses and stores 20 or commercial buildings of one or two stories in height for which our system of building construction is best adapted although the invention is not limited thereto.

For the purpose of illustration of a building 25 constructed in accordance with our invention, we have shown a one-story structure in side elevation in Fig. 1 and the side wall includes the vertical columns 1, 2 and 3, the panels 4, 5 and 6 between the columns 1 and 2 and 7, 8, 9 and 10 30 between the columns 2 and 3. Between the panels 4 and 5 and 5 and 6 there is a horizontal belt course 11 and there is a similar belt course between the panels 7 and 8, 9 and 10.

The purpose of this invention is to provide a 35 prefabricated structure and thus columns are pre-cast at the factory and panels and window and door framing as indicated at 12 in Figs. 1 and 3 are also pre-formed and delivered to the building site for erection. It will be understood 40 from the cross section Fig. 2 that the walls are formed of inner and outer spaced panels, the outer panels 5, 8 and 9 having correspondingly formed inner panels 5a, 8a and 9a. These may be formed of any convenient material utilized 45 for building construction such as concrete or like material that may be pre-cast and of sufficient strength and rigidity for the purpose. For the erection of the panels the columns, it is pointed out that the columns, for instance the column 1, 50 in the structure shown, has grooves 13 and 14 on one face to receive the end of the panels 15 and 16 and is grooved also on another face to receive a tongue on the pre-cast frame 12 of the window 13 and that this frame also is grooved 55 on the opposite vertical side to receive edges of the panels 5 and 5a.

Thus, subsequent to the preparation of the foundation, the columns are first erected and the panels then by proper hoisting equipment raised 60 to the top of the pairs of columns and moved down the grooves thereof until each wall section is completed. Between the panels forming the walls is placed an insulation such, for instance, as rock wool or any adaptable form of heat and 65 cold insulating material indicated at 17. It is possible for buildings of one or two stories, to form the columns in single lengths but it is possible that these columns may be made in sections and necessarily so for construction of buildings 70 of several stories in height in order that the pre-cast units may be conveniently handled by ordinary trucking equipment.

A cross section of the wall taken on line 4—4 of Fig. 1 is shown in Fig. 4 and it will there be 75 seen that the lower panel 4 may extend to below

the ground surface and may even extend to the footing although it is shown here as terminating at the dotted line 18. The column is notched in its outer face to receive a metal beam, here shown as an I beam 19, which extends from column to column and supports the outer edge of the floor slab 20 which terminates at or close to the inner face of the outer panel 4. This floor slab 20 and ceiling slab 23 may be cast in place or formed of separate pre-cast blocks. The belt 10 course or element 11 is grooved longitudinally to receive the upper edge of the lower panel 4 and recessed or otherwise formed as hereinafter shown to receive the lower edge of the next upper panel 5 while the upper belt course 11a is likewise arranged to receive the upper edge of the panel 5 and lower edge of the panel 6.

The columns are also notched at the proper heights to receive the I beam 22 and the ceiling slab 23 (similar to the floor slab 20) has its outer 20 peripheral edge resting upon the beams. Thus these slabs are sustained in position and insulation 17 is filled in between the wall panels as each course of panels is erected.

The manner of sustaining the inner and outer 25 wall panels from displacement is shown more clearly in Figs. 9 and 10. In Fig. 9 the belt course or member 11 is shown as having a groove 24 to receive the upper edge of a lower panel, as for instance the panel 4, while the upper 30 edge of the horizontal member 11 is formed to provide a ridge 25 having angular side portions and the bottom edge of the next upper panel 5, for instance, is formed with a corresponding V groove to fit thereover. A filler as, for instance 35 cement 25, is provided between the panel 5 and the ridge 25. It is to be noted that this construction is of considerable importance as the upper face of the belt element 11 is exposed to the elements and water might pass between the panel 40 5 and belt member 11 but due to arranging this with an inclined face as stated, water will not move upwardly through the inner face of the outer wall. Also, by this arrangement, the lower edge of the panel 5 is held from displacement 45 equally as well as the upper edge of the member 4 which fits into a groove in the lower edge of the belt element 11.

The inner slabs also require to be sustained in some structures particularly if there be a considerable distance between columns. For this purpose, we provide a metal U shaped channel 27 for the upper edge of the lower panel 4a opposite the outer panel 4 and a similar U channel 28 50 reversely positioned to receive the lower edge of the inner wall panel 5a. These extend to the inner face of the inner wall panel 4a and 5a and a finish strip 29 may be secured thereto in any approved manner as by providing an upper hook end 30 which fits within the inner flange of the channel element 28. This finish strip has an inwardly extending flange 31 at its lower edge extending to contact with the inner face of the lower panel 4a. A screw 32 may be provided for securely fastening the finish strip in place. The lower channel 55 member 27 in the construction here shown has an eye member 33 secured thereto to receive an end 34 of the tie bolt or rod 35. The opposite end of this tie bolt is formed with a hook portion 36 which engages in an eye 37 that is pre-cast in the 60 belt element 11 and likewise formed with a bent end 38 to prevent its withdrawal. The belt element 11 is provided with a recess 39 into which the eye portion extends and permitting the hook end 36 to be introduced into the eye 37. 70 75

In the erection of the panels, the bottom panel elements 4 and 4a for instance, of the two wall structures are introduced between the columns, the belt portion laid on the top of the panel 4a and the bottom channel 27 carrying the spanner wall retainer 35 on the top of the member 4a after first introducing the hook end 36 over the eye 37 and then the upper panels 5 and 5a are positioned and the inner finish strip 29 mounted on the flanges of the two channel members 27 and 28, then the next panel elements 5 and 5a are positioned in respect to the belt and the channel elements as before described. The vertical height of the panels may vary and there may be more than two belt courses 11 as is shown in Fig. 2. These belt courses are preferably spaced a distance apart approximately equal to the height of a window or door frame element placed therebetween to provide a continuation thereof from post to post as is the case with the window frame shown in Fig. 1.

The inner finish strip may be of various forms, an alternative form being shown in Fig. 11 wherein the finish strip 29a is of rectangular form having an upper hook end 30 to engage over the channel elements 27 and 28 as in the form shown in Fig. 9. The finish strip 29a may be secured in place by a screw 31a.

It is to be noted that the lower panel element 4, as shown in Fig. 3, extends to below the ground surface to the footing and may rest on a block 90. This block 90 may be grooved to receive the lower edge of the panel and it may be cemented in place as indicated at 91. One purpose of this arrangement is to properly support the lower panel and panel structure thereabove in the one-story structure shown and this arrangement also prevents rodents from entering the building from below the floor line. It is also to be noted that the panel 4, when formed, may be provided with a series of studs shown at 21 in Figs. 3 and 4 for the floor slab and similar studs 21a for the roof slab 23 as shown in Figs. 3, 4 and 18. This arrangement is utilized when the floor and roof slabs are formed in place. If the roof and floor slabs were formed in small pre-cast units as 92 which would run from one side beam 19 of Fig. 3 to a beam in the opposite wall, we provide the panel 4 with threaded inserts 93 of any approved form and placed in position at the time of the forming of the panel. At the time of erection, we provide an angle iron 94 which is secured to the inserts by a bolt 95 for each insert and similarly secured to the floor slab by bolts 96. Thus, with either of the forms shown, the panel is supported by the floor and if the building be of more than two stories height the lower slab of each story will be likewise supported to relieve the lower panels of the weight of the upper panels but such supporting of a lower panel is unnecessary if the weight to which the lower panel is subjected is not so great as to injure the panel which is of a light weight construction.

A feature of the invention is in the provision of the pre-cast frame elements for window or door openings, which frame elements are constructed for the construction of the hollow wall and columns utilized as a part of the structure. Such a window frame is shown in section in Fig. 7 in which the wall panels 5 and 5a are shown and also the pre-cast window frame indicated at 40. This frame is formed preferably of the same material as the panel members or columns and is grooved as at 41 and 42 to receive the vertical edges of the panels 5 and 5a and on the other side is shown as formed with a comparatively wide

tongue 43 fitting a groove 44 in the vertical side of the column 1 which, on its other side, is formed with grooves 45 and 46 to receive the panels 47 and 48 of the side wall of the building.

The pre-cast window frame may be reinforced with metal rods as indicated at 49 and the tie members 50 which preferably extend about all four sides of the window frame. In the construction shown in Fig. 7, a metal window frame 51 is positioned in the frame 40 at the time it is cast and a metal window sash 52 of any approved construction may be mounted in the frame. However, in so far as the pre-cast window frame 40 is concerned, the framing to receive the window or the door is not of necessity made of metal as wood framing elements for the window may be mounted in the pre-cast frame.

A feature of the door and window frame construction is in the provision of a pre-cast frame for association with columns and wall panels or wall panels only as is the case with the window 53 shown in Fig. 1 in which case both vertical sides of the window frame have parallel grooves similar to the grooves 41 and 42 of Fig. 7 to receive the panels 3 and 9 and corresponding inner panels as well as the upper panels 10, lower panel 7 and corresponding inner panel. While a door frame is not shown in the drawings, it is of the same character of construction as the window frame. The said belt element is formed with a tongue on its end section abutting the frame as shown at 53 in section in Fig. 16.

As previously stated, the floor and ceiling slabs extend between the columns to the vertical outer wall panels. These slabs are sustained at their outer edges by beams as 19 and 22 carried by the columns and it is pointed out that, at the columns which form the corners of the building, there is provided in the pre-fabricated column a right angle metal plate 55, one side of which is attached to a longitudinally extending beam as 19 on one side and the other leg extending to a horizontal beam 56 and thus the floor or roof slab is supported at its periphery on the metal I beams. In the intermediate column such as the column 2, there is provided at the time of forming a metal plate 57 which extends transversely of the column and projects on opposite sides thereof to which beams 56 and 56a are secured. These beams are positioned between the outer and inner vertical wall panels.

The columns likewise are preferably reinforced as shown in Fig. 8 by metal rods 58 and transverse tie elements 59 and in the construction shown in Fig. 8 are shown the outer and inner wall panels and this intermediate column is also grooved to receive an intermediate panel 60 forming a partition extending transversely of the building and which is but a single wall as insulation is not generally required between rooms of a building. However, if so required, it is to be understood that spaced walls may be provided to extend into corresponding notches in the column to provide an insulated partition element. It is thus to be seen that the floor elements are sustained on pre-fabricated I beams supported by the columns which columns have brackets to which the beams are attached, the brackets being introduced in the columns at the time of the fabrication thereof.

It is desirable that a finished ceiling be provided below a roof element such as the slab 23 or a second story floor as the case may be. The ceiling element is of pre-fabricated construction formed of light weight panels or blocks such as

are indicated generally in Figs. 12, 13 and 14 and that the ceiling is to be supported at some little distance below the upper floor or roof slab as the case may be. Both the floor slab 20 and the 5 roof or second floor slab 23 are supported upon the marginal iron beams as heretofore stated, but if these slabs are pre-fabricated, they are made in sizes capable of being handled and extend from beam to beam in the opposite side 10 walls.

The ceiling proper is indicated at 61 in Fig. 4 and is shown in Fig. 3 as consisting of a series of panels which may be of various shapes but here shown as, and preferably are, of rectangular 15 form in outline. These slabs have a finished under surface ready to receive a decoration as is also the case with the inner walls and other structure such as window or door frames. The ceiling element is suspended below the ceiling or floor slab 20 23 and is spaced therefrom as shown in Figs. 3, 4 and 12. This spacing may receive a piping or conduits of any type that may be required in a building and where necessary, piping or conduits (not here shown) can be introduced between the 25 vertical wall panels. What we have termed the "finished" ceiling 61 is formed of a series of slabs as heretofore stated which require to be suspended from the floor or roof slab 23. For this purpose, in the formation of the roof or floor slabs 23, 30 we provide inserts 63 which are of a tubular form as shown in Fig. 12 and have portions such as 64 extending into the floor slab and positioned therein at the time of forming the slab which tend to prevent withdrawal of the inserts from 35 the slab. The lower end of the tubular insert is open to receive a hook 65 of a link 66 which is hooked over a bar 67 in the insert. The lower end of the link 66 is also formed with a hook portion 68 which supports an I beam 69. After the 40 floor slabs are erected and the beams 69 placed thereacross in sufficient number, the ceiling slabs 62 may be positioned.

The ceiling slabs also have metal inserts 70 of hollow form and shaped to prevent withdrawal 45 and formed in the slab 62 at the time it is made. This insert has a bar 71 about which the hook end of a rod 72 may be introduced. This rod 72 has an upper end 73 of hook form to engage over the upper edge of a channel beam 74 running 50 transversely of the beam 69. There are thus a series of parallel beams 69 running in one direction and parallel beams 74 at a right angle thereto below the roof element. The slabs 62 forming the finished ceiling usually have four inserts 70 adjacent the corners and the link 72 hooks over 55 the channel beams 74. These beams 74 are sustained in position by a link 75 having a hook end 76 engaging beneath the beam 74 and also has a hook end 77 engaging over the beam 69. Thus 60 the beams 74 are suspended from the beams 69 and a turn buckle 78 is provided between the links 75 and 77 respectively having threaded ends for the opposite ends of the turn buckle. The beams 69 and 74 are provided to permit ready assembly of the ceiling panels to the roof as the inserts in the roof slab and panel are not usually 65 in vertical alignment. With a slab thus suspended by the described adjustable means, the ceiling panels may be leveled. Thus each of the ceiling 70 panels except some last one thereof are suspended one by one and adjusted to the proper level. The edges of the slabs 66 are grooved as indicated at 75 79 and are spaced a slight distance apart as shown in Fig. 12 to receive a grouting which is forced into the crevices and up into the enlarged

portion formed by the adjacent grooves 79. This enlarged portion of the grouting forced into the grooves prevents the cement or grouting from dropping out after it has once set.

Each of the ceiling panels 62 are thus erected 5 one at a time and leveled up as the space between the panels and roof slab permits the workman to engage the hooks over the respective beams and adjust the turn buckles. However, there remains one panel of finished ceiling indicated at 80 in Fig. 13 to be erected. This panel 10 80 requires a little different treatment than the others because the last slab closes the only opening to above the ceiling and has to be handled from below. For this purpose, as shown in Fig. 14, the link 72a, which corresponds to the bar 72 of Fig. 12, extends through the ceiling panel 15 which is apertured for the purpose and formed with a recess in its under face indicated at 81. A nut is placed on the projecting end of the rod 20 72a permitting the block 80 to be leveled. The rod 72a has a hook end similar to the rod 72 of Fig. 12 to hook over a convenient beam 74 and has its edges provided with the grooves shown at 25 79 in Fig. 12 so that it may be cemented in place. This finishes the erection of the preformed finished ceiling panels and provides a surface to 30 receive a decoration of any convenient type, as paint, paper, calsofine or the like or the blocks themselves may be formed with a surface that 35 provides the finish as, for instance, by forming the surfaces of the blocks 62 and 80 with a glazed and colored surface. This, however, is inconvenient where the grouting lines, which will be required in such structure, are not objectionable. 40 Also, in the structure shown in Fig. 14, after the nuts have been adjusted on the rod 72a, the recess may be filled with a proper material to conceal the same and it is the intention to also use a grouting between the outer edge of the formed 45 ceiling member where it contacts with the wall surfaces.

Where it is desired to form columns of such length as not to be readily transportable if 50 formed of a single piece they may be formed in sections. In such case, the lowermost section such as the section 82 of Fig. 15 is formed with four rods 83 which project upwardly from the 55 end of section 82. The next upper section 85 of the column may be formed with four openings 84 as, for instance, by introducing a metal tube in the form in which the columns are cast so that the tubes will cast in place and these tubes extend upwardly from the lower end of the upper section 85 for the full length of the projecting ends of the rod 83 and then are 60 outturned as indicated at 86 and open through the surface of the column section 85. These column sections are erected as shown in Fig. 15, with the projecting ends of the rods 83 of the 65 lower section 82 extending into the tubes 86 of the upper section 85. Cement may then be poured into the open ends 86 of each of the tubes and thus cement the rod ends in place in the section 85. For the purpose of strengthening the lower end of the section 85, tie irons or 70 cables 87 may be wound around the tubular elements after the manner indicated in Fig. 16. By this means, columns can be made in sections of sufficient strength and of lengths that may be 75 readily handled and likewise the rod ends that are inserted in the section 82 may be tied together as by wire or cable 88. When the columns and sections are erected, the building is constructed by first erecting the bottom column 75

sections, filling in the side wall panels and window frames and door frames where necessary, as hereinbefore described, and then the second column sections are erected and the rod ends cemented in place as described and thereafter the panels and belt courses etc., forming the wall sections are erected in the same manner as the first.

In the foregoing description, the various necessary structural elements and relationship thereof have been described. The purpose of pre-fabrication is to secure material at the least cost possible which may be transported to a building site and there erected after the general manner herein disclosed to secure an inexpensive but serviceable structure for various purposes as dwellings, stores, garages or even buildings of two or more stories in height.

It will be noted from the foregoing, that by making this material on a production basis at a plant equipped for the purpose, the various elements required for the formation of the structure may be made of comparatively cheap material and at little labor cost and that the building may be constructed without the requirement of highly skilled mechanics and in a minimum of time and therefore at the least possible expense. Thus, through the formation of the various elements for quick erection, we have provided a system of building construction that attains this principal object of lessened cost in materials and in time and with hand labor of the partially skilled type.

It is believed from the foregoing description, that the various features and objects of the invention are attained by the structures as described and their mode of assembly and it is pointed out that various changes and modifications may be made in one or more of the elements without departing from the spirit and scope of the invention as set forth in the appended claims.

Having thus fully described our invention, its mode of operation, what we claim and desire to secure by Letters Patent of the United States is—

1. In building construction, a pair of pre-cast column elements, each having a pair of parallel vertical grooves in the respective opposed faces, an inner and outer wall element, each comprising panels in a vertical plane for engaging in the respective grooves providing a hollow wall section therebetween, an element providing a horizontal belt course extending from column to column and positioned between the opposed horizontal edges of the successive vertical panels forming the outer face of the wall in a tongue and groove relationship therewith.

2. In building construction, a pair of pre-cast column elements, each having a pair of parallel vertical grooves in the respective opposed faces, an inner and outer wall element, each comprising panels in a vertical plane for engaging in the respective grooves providing a hollow wall section therebetween, a unitary pre-cast frame element for defining an opening in the wall and assembled in a tongue and groove association with the said panels, and an element providing a horizontal belt course extending from column to column and positioned between the opposed horizontal edges of the successive vertical panels forming the outer face of the wall in a tongue and groove relationship therewith.

3. In building construction, a pair of pre-cast column elements, each having a pair of parallel

vertical grooves in the respective opposed faces, an inner and outer wall element, each comprising panels in a vertical plane for engaging in the respective grooves providing a hollow wall section therebetween, an element providing a horizontal belt course extending from column to column and positioned between the opposed horizontal edges of the successive vertical panels forming the outer face of the wall in a tongue and groove relationship therewith, panel supporting means between the horizontal edges of the successive vertical panels of the inner wall element, and means connecting the said belt course with the said panel supporting means.

4. In building construction, a pair of pre-cast column elements, each having a pair of parallel vertical grooves in the respective opposed faces, an inner and outer wall element, each comprising panels in a vertical plane for engaging in the respective grooves providing a hollow wall section therebetween, a unitary pre-cast frame element for defining an opening in the wall and assembled in a tongue and groove association with the said panels, panel supporting means between the horizontal edges of the successive vertical panels of the inner wall element, and means connecting the said belt course with the said panel supporting means.

5. In building construction, a pair of pre-cast column elements, each having a pair of parallel vertical grooves in the respective opposed faces, an inner and outer wall element, each comprising panels in a vertical plane for engaging in the respective grooves providing a hollow wall section therebetween, an element providing a horizontal belt course extending from column to column and positioned between the opposed horizontal edges of the successive vertical panels forming the outer face of the wall in a tongue and groove relationship therewith, an element having an upper and a lower groove positioned between the horizontal edges of the successive vertical panels of the inner wall element, and means connecting the belt course of the outer wall panel with the said grooved element of the inner wall panel.

6. In building construction, a pair of pre-cast column elements, each having a pair of parallel vertical grooves in the respective opposed faces, an inner and outer wall element, each comprising panels in a vertical plane for engaging in the respective grooves providing a hollow wall section therebetween, an element providing a horizontal belt course extending from column to column and positioned between the opposed horizontal edges of the successive vertical panels forming the outer face of the wall in a tongue and groove relationship therewith, and a finish strip on the inner face of the inner wall panel supported by the inner portion of the said grooved element.

7. In building construction, a floor slab, supporting means therefor including column elements, a finished ceiling depending from a floor slab, said ceiling comprising a series of panel like elements and means for suspending the panel elements relative to the floor slab thereabove, said means comprising a beam extending beneath the floor slab, a sustaining rod engaging the beam element at its lower end, means for securing the upper end of said rod in the floor slab, means for suspending each ceiling panel from the slab comprising an element secured to the said beam, an element secured to a panel, an adjusting means between the said two last named elements by means of which the ceiling panels may be positioned to occupy substantially the same plane,

the abutting edges of the ceiling panels being grooved, a cementitious grouting in the grooves forming a connecting element between the said panels, one panel of the group of ceiling panels having apertures therein, and a rod extending from each of the apertures to the said beam, the projecting end of the rod being threaded to receive a nut and the exposed lower face of the said one panel being recessed to receive a nut whereby the said one panel of the series may be adjusted from a position below the lower face of the panel.

8. In building construction, a column formed of vertical sections, the upper end of a lower section having a series of rods embedded therein at

one end and projecting thereabove, reinforcing means about the ends of the rods embedded in the said column section, the lower end of an upper column section having a series of apertures therein to receive the projecting rod ends of the 5 lower section, the said apertures extending vertically a distance in the column and at the upper ends extending outwardly and opening through the face of the column to receive a cementitious material subsequent to erection of the sections, 10 and reinforcing means in the lower end of the upper section extending about the series of apertures therein.
